(57) **CLAIM**

The ornamental design for a wood chipper as shown and described.

DESCRIPTION

FIG. 1 is a front perspective view of a wood chipper showing my new design;

FIG. 2 is another front perspective view thereof;
FIG. 3 is a back perspective view thereof;
FIG. 4 is another back perspective view thereof;
FIG. 5 is a left side view thereof;
FIG. 6 is a right side view thereof;
FIG. 7 is an enlarged perspective view of a portion of the wood chipper within the area identified by broken circle "7" in FIG. 1;
FIG. 8 is an enlarged perspective view of a portion of the wood chipper within the area identified by broken circle "8" in FIG. 1;
FIG. 9 is an enlarged perspective view of a portion of the wood chipper within the area identified by broken circle "9" in FIG. 1;
FIG. 10 is an enlarged perspective view of a portion of the wood chipper within the area identified by broken circle "10" in FIG. 1;
FIG. 11 is an enlarged perspective view of a portion of the wood chipper within the area identified by broken circle "11" in FIG. 1;
FIG. 12 is an enlarged perspective view of a portion of the wood chipper within the area identified by broken circle "12" in FIG. 1;
FIG. 13 is an enlarged perspective view of a portion of the wood chipper within the area identified by broken circle "13" in FIG. 1;
FIG. 14 is an enlarged perspective view of a portion of the wood chipper within the area identified by broken circle "14" in FIG. 2;
FIG. 15 is an enlarged perspective view of a portion of the wood chipper within the area identified by broken circle "15" in FIG. 2;
FIG. 16 is an enlarged perspective view of a portion of the wood chipper within the area identified by broken circle "16" in FIG. 2;
FIG. 17 is an enlarged perspective view of a portion of the wood chipper within the area identified by broken circle "17" in FIG. 3;
FIG. 18 is an enlarged perspective view of a portion of the wood chipper within the area identified by broken circle "18" in FIG. 3;
FIG. 19 is an enlarged perspective view of a portion of the wood chipper within the area identified by broken circle "19" in FIG. 3;

(Continued)

FIG. 20 is an enlarged perspective view of a portion of the wood chipper within the area identified by broken circle "20" in FIG. 4;

FIG. 21 is an enlarged perspective view of a portion of the wood chipper within the area identified by broken circle "21" in FIG. 5; and,

FIG. 22 is an enlarged perspective view of a portion of the wood chipper within the area identified by broken circle "22" in FIG. 6.

The long dash short dash broken line showing in the figures is included for the purpose of illustrating the border of the enlarged views in the drawings and forms no part of the claimed design.
